UNITED STATES PATENT OFFICE.

ARTHUR RUSSELL, OF BALTIMORE, MARYLAND, ASSIGNOR TO THE RUSSELL RADIO CORPORATION, OF BALTIMORE, MARYLAND, A CORPORATION OF MARYLAND.

VARIABLE CONDENSER.

Application filed February 3, 1925. Serial No. 6,501.

To all whom it may concern:

Be it known that I, ARTHUR RUSSELL, a subject of the King of Great Britain, residing in the city of Baltimore, State of Maryland, U. S. A., have invented certain new and useful Improvements in Variable Condensers, of which the following is a specification.

One of the important difficulties incident to the operation of radio receiving sets, is that incident to tuning in on the various stations which in the main consists in adjusting the condenser to the particular wave length of the sending station from which it is desired to receive. The commonest type of variable condenser consists of a stator composed of a series of stationary spaced metal plates and a rotor consisting of a second series of rotatable spaced metal plates which intermesh with the plates of the rotor, and are spaced therefrom by a suitable air gap. The stator plates are insulated from the rotor plates and all of the plates are in planes at right angles to the axis of rotation.

In the present well-known type of variable condenser thus described, the desired adjustment as to wave length is obtained by moving the rotor about its axis relatively to the stator so as to change the relation of the plates, changing the cross-section of the air gap between the plates of the stator and the plates of the rotor without changing the spacing, ordinarily termed the width of the air gap.

The dial by which the rotor is turned and by which its position is indicated, is ordinarily connected directly to the axis of the rotor, and the adjustment requisite to satisfactory results is so fine as to make it exceedingly difficult to obtain in this way, wherein is involved the necessity for a high degree of skill on the part of the operator. A further difficulty is that the variation or band of wave lengths obtained by the adjustment of such a condenser is much more limited than is found desirable by the average operator. Also such condensers are easily gotten out of order by slight deflection or bending of the plates, and there is no way of adjusting them to the capacity of the particular set in which they are to be installed, making it necessary for the manufacturers to make and the dealers to carry in stock condensers of various capaci-

ties having different numbers of plates and further making it necessary for the radio enthusiast who rebuilds his set, to change and possibly discard his condenser with corresponding frequency and expense.

The present invention eliminates and overcomes to a large degree the defects and difficulties thus presented, giving a much finer adjustment to wave lengths with a less exercise of skill on the part of the operator, at the same time providing for adjustment or tuning of the apparatus to a much greater variation, or as it is stated in the terminology of the art, to a much broader band of wave lengths than any of the condensers now in use.

Also the apparatus permits of an easy and quick adjustment as to its capacity, so that for the ordinary commercial apparatus it is only necessary to manufacture a condenser of a single capacity, and it is only necessary for the dealer in such commercial apparatus to carry a single condenser or condensers of a single capacity in stock, and the radio enthusiast or amateur who rebuilds his set may change the capacity of his condenser at will to conform to the corresponding change in his set. The improved condenser may be produced economically at decreased expense compared to the present type, and it is so constructed that it is less apt to get out of order than are the commercial types of condenser now in use, and it may therefore be described as of longer life or longer average life.

In general terms the improved apparatus may be described as having the stator and rotor each in the form of a wide band or plate. The two plates are spaced apart at all points and insulated, and as shown they are curved about a single axis at a uniform pitch or angle to the radially opposite and corresponding points of any circle drawn about the same axis as a centre. Preferably the plates are spirally wound or coiled after the manner of a clock spring, the width of the plates being parallel to the axis, and one plate is enclosed within the other. As shown, the rotor is enclosed within the stator, i. e., has each turn, loop or coil placed between two corresponding turns or coils of the stator, so that the two plates or bands are substantially concentric and parallel and rotatable through an arc, one relatively to the other.

Rotation or change of angular position of one plate relatively to the other on account of the equal and uniform pitch maintains the parallel relation and gives a change of 5 spacing of the plates and a wide change of capacity of the condenser. In the form shown the stator plate or spiral is secured to the panel and the rotor is mounted on a shaft for angular adjustment relatively to 10 the stator about the axis of the stator and its own axis which are preferably identical. For the purposes of this adjustment as to capacity, I have provided a dial or similar member connected to the rotor by which it 15 may be rotated and its position relatively to the panel and the stator suitably indicated.

For the purposes of adjustment of the apparatus to the wave lengths of the various 20 stations from which it is desired to receive, one of the plates is moved relatively to the other in a direction parallel to the axis in any suitable manner. Preferably the rotor is mounted to move along the shaft into and 25 out of the stator, changing the cross-section of the air gap. In the form shown the adjustment as to wave lengths is obtained by means of a screw threaded, axially placed rod or pin extending through the shaft on 30 which the rotor is mounted, by which threaded pin the rotor is moved in the direction of its axis relatively to the stator by turning a suitable nut or knob engaging the thread, giving an exceedingly wide range 35 of adjustment, making it possible to change the cross-section of the air gap from zero to the maximum available when the rotor is almost or completely enclosed within the stator. The rotor is during this operation 40 held against rotation by means of a suitable key or equivalent device which connects it to the shaft with which it is turned during the capacity adjustment.

The axial adjustment provides for variation of the cross-sectional area of the air gap and by means of the screw and knob a much finer adjustment as to this element, which tunes the set to the wave length of the sending set, may be obtained than with 45 the type of condenser in which the rotor plates are merely swung by means of and with the dial, and at the same time this apparatus obtains or provides for an adjustment to a greater variation of wave length 50 or broader band of wave lengths than can be obtained by any other known instrument now provided for this purpose.

In the accompanying drawings I have 55 illustrated a variable condenser embodying the features of my invention in the preferred form.

In the drawings—

Figure 1 is a longitudinal section on the 60 plane of the axis of the condenser plates showing the complete condenser assembled.

Figure 2 is an elevation looking at the condenser plates from the right in Figure 1, i. e., from the rear of the panel. The adjustment is for minimum capacity.

Figure 3 is an elevation corresponding to 70 Figure 2, showing the plates in a slightly different position of adjustment by relative rotation to provide for variation of capacity. The adjustment is for maximum capacity. 75

Figure 4 is an elevation looking at the front of the panel showing the dial, knob, etc., at minimum capacity.

Figure 5 is a section on the line 5, 5 of 80 Figure 1 through the hollow shaft, screw-adjusting pin and hub, showing the stop which limits the rotation of the hollow shaft and therefore the angle through which the plates may be rotated to adjust for capacity. 85

Referring to the drawings by numerals, each of which is used to indicate the same or similar parts in the different figures, the variable condenser as shown comprises concentric and substantially parallel condenser 90 plates, one enclosed within the other and indicated by reference characters 1 and 2, the plates being shown each in the form of a coiled or spiral band having their width parallel to the axis of the spiral and each 95 having its respective turns equally spaced and substantially parallel, the pitch being uniform throughout, and as is usual in such apparatus, the stator 1 is insulated from the rotor 2. 100

The stator 1 is secured to the panel 3, or more properly to the condenser base 4 by means of suitable clips or brackets 5 which may be soldered to the stator plate and by screws 6 engaging the brackets 2. 105 The base 4 is in turn secured to the panel. Both the base 4 and the panel 3 are of hard rubber or other suitable insulating material. The stator plate 1 is preferably spaced away from the base, as indicated at 7. The plates may be connected to the circuit in the usual manner as at 6 and 6'. 110

The loops or turns of the stator plate 1 are spaced apart and secured in the desired relation, and the entire stator coil structure 115 is made rigid by radially placed studs or other suitable means 9 connecting the respective loops or turns 10, 11, 12, 13 of the stator plate or coil at the base thereof, i. e., adjacent the edges of the plate which are nearest the panel, see Fig. 1, so that they do not interfere with the entrance of the rotor plate between the respective loops or turns of the stator plate, and the loops or turns of the stator plate 2 are similarly braced by radial studs 15 connecting them at their outer edges, i. e., the edges remote from the panel, see Fig. 1, so that these studs or struts 13 interfere as little as possible with the entrance of the rotor plate 2 to the full 120 125 130

width of the plate between the turns or coils of the stator plate 1. The two spiral plates 1 and 2 being concentric, and the plate 2 being enclosed within the plate 1, the respective turns of the rotor plate 2 are at the position of minimum capacity, Figure 2, preferably spaced halfway between the respective turns or loops of the stator plate 1. There is in the form of the invention shown 5 a spider or other suitable supporting plate 16 secured at its radial ends within the inner turn or loop 17 of the rotor. This support 16 carries a central hub 18 to which is secured a pin 19. The pin 19 is concentric 10 and aligned with the axis of both plates, being as aforesaid secured at one end to the centre of the rotor plate 2 and extending forwardly through shaft 22 which is made hollow to receive it, through the stator plate 1, through the panel and projecting beyond the panel for a sufficient length to provide 15 for adjustment of the plate 2 in the direction of its axis for a large proportion of the width of the plates. The forward end of 20 the pin in front of the plates is threaded at 20 to co-operate with a nut or knob 21, suitably apertured and threaded to co-operate with the thread on the pin. The pin 19 is mounted to slide in the hollow shaft 22 25 which is concentric and aligned therewith and mounted in a bearing formed in a boss 24 which as shown is formed integral with a plate 25 secured in any suitable manner to the condenser base or base plate 4 or to the panel 3.

The shaft 22 referred to hereinafter as the rotor shaft may be actuated and controlled, and its position determined by a dial 26 suitably apertured at its centre to admit 30 the shaft and secured thereto in any suitable manner as by means of a set-screw 27. This dial may be suitably graduated at 28, see Fig. 4, and the panel may be provided with a pointer 29 to co-operate with the 35 graduations. The resistance or friction of the panel is adjusted by means of a screw 40 seated in the dial and bearing on the panel.

The rotor shaft 22 may be connected to 45 the rotor 2 in any suitable manner to cause the rotor to turn with the shaft 22 and to permit the rotor to slide freely in the direction of the axis of the shaft. In the form of the invention shown this keying arrangement consists of a pin 30 parallel to the shaft 22 and the pin 19 and spaced well 50 away from the shaft and pin 19, and secured at one end to the support or plate 16 which spans the outer end of the rotor and extending toward the panel. This key pin 30 in the form of the invention shown, slides in a bearing 31 formed integral with a radial arm 32 on the hollow rotor shaft 22.

As shown, the radial arm 32 terminates 55 in a flange 33 on shaft 22 which serves to

position the rotor shaft 22 by contact of the flange with the end of the boss 24, the hollow rotor shaft 22 being thrust forwardly, maintaining the flange 33 in contact with the end of the boss by means of a coil spring 34 which is coiled about the rod 19 at the rear, bearing at one end against the forward side of the spider plate 16 and at the other end against the flange 33. This spring also tends to thrust the rotor plate rearwardly, 70 i. e., to the right in Figure 1, causing it to move to the right out of the stator as the rod 19 is released by unscrewing the knob or nut 21 and permitting it to be drawn to the left, causing it to enter the stator as the nut or knob is turned up on the rod 19, giving the desired adjustment of the cross-section of the air gap to provide for interpreting different wave lengths.

The rotation or angular displacement of 85 the rotor 2 from minimum capacity position relatively to the stator 1, is definitely limited by means of a radially projecting stop 36, see Fig. 5, on the rotor shaft 22, which rides in an open slot 37 at the end of boss 24. 90

The minimum capacity position of the rotor, Fig. 2, is determined by the contact of the stop 36 with the edge 39 of the slot 37, and the maximum position, Fig. 3, by contact with the opposite edge 38. The spacing 95 of the plates is thus changed and the parallel relation maintained by and on account of the concentric location of the plates and the uniform pitch. These elements may be varied to some degree without complete loss of 100 the function.

In the operation of the condenser, to adjust for capacity to adapt the condenser to any particular receiving set, the rotor 2 is turned from the position shown in Fig. 2 105 to the left relatively to the stator 1 toward the position in Fig. 3 to reduce the spacing of the plates, causing the loops or turns of the rotor by the variation in radius of the stator and rotor, to approach the loops of 110 the stator, thus changing the width of the air gap and varying the capacity of the condenser. The manner of obtaining the opposite adjustment is apparent.

While the prior art includes condensers in 115 which one or more plates of one element are adjusted toward and from the adjacent plates of the other element, the rotation of the present type of condenser whereby the spacing of the entire rotor relatively to the stator is changed by a single adjustment by rotating one element relatively to the other about the common centre, is regarded as an important feature of the invention, producing a wide scope of adjustment as to capacity 120 without complication of structure and by a very simple operation.

To tune the receiving set to the wave lengths of any transmitting set from which it is desired to receive, the cross-section 130

of the air gap is changed. An exceedingly fine adjustment is obtained by rotating the nut or knob 21 either taking up or letting out the threaded pin 19, moving the rotor 5 relatively to the stator in the direction of the common axis, changing the position of the rotor 2 as to the extent to which it is enclosed within the stator 1, and while a very minute adjustment may be easily obtained in this way, there is on account of the wide possible variation of position of the rotor 2 relatively to the stator 1, a wide range of adjustment, and the apparatus 10 may be adjusted with extreme accuracy and 15 without the exercise of skill requisite with the condensers now in use, to and through a broad band of wave lengths, than can be covered by any of the condensers previously in use.

20 I have thus described specifically and in detail a single embodiment of my invention in order that the nature and operation of the same may be clearly understood; however, the specific terms herein are used descriptively rather than in a limiting sense, the scope of the invention being defined in the claims.

What I claim and desire to secure by Letters Patent is:

- 30 1. A variable condenser having a rotor and a stator each comprising a plate wound in a spiral about the mutual common axis, the two plates being adapted to intermesh with and being spaced from each other, and 35 means to change the relative spacing between the plates by relative rotation of said rotor and said stator about the common axis.
2. A variable condenser having a rotor and a stator each comprising a plate wound 40 in a spiral about the mutual common axis, the two plates adapted to intermesh with and being spaced from each other, means to adjust one of said plates relative to the other in the direction of the common axis, and means to move one of the said plates angularly about the common axis

with regard to the other plate to vary the relative spacing between said plates.

3. In a variable condenser, a stator plate in the form of a rigid spiral of uniform pitch; a rotor plate in the form of a rigid spiral of uniform pitch, said plates having the same uniform spacing along a radius and adapted to be intermeshed with each other, means to adjust the relative spacing of the turns of one plate with regard to the adjacent turns of the other plate, and means to hold said plates against variation of said spacing.

4. In a variable condenser, a stator plate in the form of a rigid spiral, a rotor plate in the form of a rigid spiral, said plates having the same uniform spacing along a radius and adapted to intermesh with each other, the outer ends of one of said plates having a greater spacing from the adjacent turn of the other plate than the said uniform spacing, and means to vary the length of the outer end portion of said first plate having said greater spacing.

5. In a variable condenser, a stator comprising a metal plate in the form of a spiral having a uniform angle of intersection with a radius, a rotor plate similarly formed and adapted to intermesh with the stator, so that the turns of the respective plates are uniformly spaced along a radius, a hollow shaft for the rotor with keying means permitting the rotor to slide in the direction of its axis and securing it to the shaft to rotate therewith, a threaded pin extending through the hollow shaft and secured to the rotor, a nut engaging the pin to move the rotor in the direction of its axis into and out of intermeshed relation with the stator plate to adjust the effective capacity, and means to turn the rotor shaft to adjust the width of the air gap between the plates to vary the effective capacity.

Signed by me at Baltimore, Maryland, 90 this 2nd day of February, 1925.

ARTHUR RUSSELL.
